UNITED STATES PATENT OFFICE.

ISRAEL L. LANDIS, OF LANCASTER, PENNSYLVANIA.

GATE.

SPECIFICATION forming part of Letters Patent No. 339,903, dated April 13, 1886.

Application filed October 15, 1885. Serial No. 180,012. (No model.)

To all whom it may concern:

Be it known that I, ISRAEL L. LANDIS, a citizen of the United States, residing at Lancaster, in the county of Lancaster and State of Pennsylvania, have invented certain new and useful Improvements in Gates, of which the following is a specification, reference being had therein to the accompanying drawings.

This invention relates to certain improvements in gates; and it has for its objects to provide a gate that may be readily elevated to any convenient height, and fastened by means of an adjustable latch; to provide for automatically opening the gate by the draft upon the latch when the bolt is withdrawn from the catch, and to provide an improved hinge to be employed in connection with the gate, and means for holding the gate upon the pintle of the hinge, all as more fully hereinafter specified. These objects I attain by the means illustrated in the accompanying drawings, in which—

Figure 1 represents a side elevation of my improved gate complete, showing the same in a closed position. Fig. 2 represents a vertical sectional view of a portion of the gate, taken on the line *y y* of Fig. 1. Fig. 3 represents a vertical sectional view of a portion of the gate, taken on the line *x x* of Fig. 1. Fig. 4 represents a transverse sectional view of the adjustable catch detached; Fig. 5, a sectional view taken at right angles to the view shown in Fig. 4; Fig. 6, a detached view of the upper hinge of the gate. Fig. 7 is a side elevation of the gate in an elevated position; Fig. 8, a detached face view of the adjustable catch and gate-post; and Fig. 9 is a top view showing the adjustable wheel.

The letters A and B indicate the respective gate-posts, and C the gate, which is hinged to the post A.

D is a vertical beam, which forms part of the gate, the said beam being slotted vertically for the passage of an adjustable bolt, E, which extends between the vertical beams F, which also form part of the gate. The bolt is provided with a nut, G, at one end, by means of which the beams D and F may be clamped together to adjust the gate, as will more fully hereinafter appear.

The letter H indicates a series of parallel bars, which are pivoted at one end between

the beams F, and at the other between similar beams, I, to permit the gate to be raised at an angle when desired. At opposite sides of the 55 said bars H are arranged the oblique bars K, which are pivoted at their upper ends to the upper ends of the beam D, as shown. Near their lower ends the bars K are connected by a screw-bolt, L, upon which is 60 mounted a friction-wheel, M, which sets between the lower ends of said bars. The bolt is provided with a clamp-nut, N, by which the bars may be drawn together and clamped upon the two lower parallel bars, the friction- 65 roller being somewhat less in thickness than the said parallel bars for the purpose. This roller permits the inclined bars to ride with but little friction upon the lower parallel bar when the gate is elevated, thus rendering the 70 operation extremely easy.

The letter P indicates the bolt of the gate, which is arranged to slide longitudinally along the top of one of the parallel rails between the beams I. The said bolt at one end is pivoted between two bars, R R', which are located on opposite sides of the gate, the bar R being pivoted at its lower end to one of the parallel bars, and the bar R' pivoted at its lower end to the opposite side of said parallel bar, as 80 shown. The bar R' is contracted at a portion of its length, so as to form a spring, and its upper end projects above the upper parallel bar of the gate, and is perforated for the attachment of the operating-cords S. To the 85 parallel bar to which the spring-bar is pivoted a slotted pawl or dog, T, is also secured in such manner that its free end may bear against the lower portion of said spring-bar, in order to regulate the tension of said bar to 90 give the bolt more or less throw, the dog being adjustably secured by a screw, T'.

To the upper end of the beam D is secured a grooved pulley or wheel, U. This wheel at its periphery is provided with an eyebolt, V, 95 through which pass the operating-cords before mentioned, the said cords being carried around the pulley or wheel in opposite directions and extended to each side of the gate. The pulley-wheel may be secured to the lateral head of the upper hinge-section, W, and bracket X, as shown in Fig. 7, or to the lateral heads of the upper section, as shown in Fig. 1, in the latter case the bracket X being

dispensed with, and the forward lateral head of the upper hinge-section taking its place. Both the bracket and hinge are slotted, as shown, and are secured by means of screw 5 bolts and nuts Y to the beams D in such manner as to be vertically adjustable. The eye-section of the hinge W is cast in one piece with the horizontal head complete. Below the lower hinge, Z, is located a wire pawl, A', 10 which may be swung under the pintle to keep the gate in position.

The letter B' indicates the adjustable catch, which consists of a rectangular frame of metal arranged to slide upon a vertical bar, C', forming part of the gate-post B. The said frame has pivoted to it a cam-lever, D', one end of which is thickened, so as to bind the frame to the bar C', and thus hold the catch in any position to which it may be adjusted. This is 15 accomplished by depressing the outer end of the lever. The catch-frame has on its inner face inclined guides leading to the recesses D', by means of which the bolt is automatically engaged to lock the gate when it closes.

20 As shown in Fig. 1 of the drawings, the upper eye-section of the hinge is cast with an elongated eye, E', and a connecting-web, F', which strengthens the hinge and enables it to stand the vertical adjustment.

25 The operation of my invention will be readily understood in connection with the above description, and is as follows: Upon pulling

upon either of the cords the spring-bar will be first drawn back, releasing the bolt from the catch. The pulley or wheel will then be 35 rotated, causing the gate to open. To close the gate, the opposite cord is drawn upon until the gate closes, when it is released and the bolt springs into the catch.

Having thus described my invention, what 40 I claim, and desire to secure by Letters Patent, is—

1. The combination, with the vertically-adjustable gate and its clamping-bolt, of the vertically-adjustable catch and the cam-lever, 45 whereby the catch is held in an adjusted position, substantially as specified.

2. The combination, with the vertical hinged beam, of the upper hinge and bracket having horizontal lateral heads, to which the pulley 50 is attached, substantially as specified.

3. The combination, in a gate, of the sliding bolt, the spring-bar to which said bolt is pivoted, and the adjustable pawl bearing against the said bar, whereby the latch is held in an 55 adjusted position, and the grooved pulley and operating-ropes, whereby the gate is opened and closed, substantially as specified.

In testimony whereof I affix my signature in presence of two witnesses.

ISRAEL L. LANDIS.
